UNITED STATES PATENT OFFICE.

LOUIS H. PERLMAN, OF NEW YORK, N. Y.

WHEEL.

1,320,909.

Specification of Letters Patent.

Patented Nov. 4, 1919.

Application filed August 16, 1917. Serial No. 186,529.

To all whom it may concern:

Be it known that I, LOUIS H. PERLMAN, a citizen of the United States, residing at New York, in the county of New York and State of New York, have invented certain new and useful Improvements in Wheels; and I do hereby declare the following to be a full, clear, and exact description of the invention, such as will enable others skilled in the art to which it appertains to make and use the same.

This invention relates to improvements in demountable rims or wheels of the type ordinarily employed as carrying wheels for automobiles.

The primary object in view is the improving of the means of anchorage for the rim locking means, having reference more particularly to the type of locking means disclosed in detail in my co-pending application Serial No. 150,487, filed February 23, 1917.

With this and further objects in view as will in part hereinafter become apparent and in part be stated, the invention comprises certain novel constructions, combinations and arrangements of parts as subsequently specified and claimed.

In the accompanying drawing,—

Fig. 1 is a transverse section through the peripheral portion of a wheel and demountable rim embodying the features of the present invention.

Fig. 2 is a vertical section taken on the plane indicated by line 2—2 of Fig. 1.

Fig. 3 is a horizontal section taken on the plane indicated by line 3—3 of Fig. 1, looking upward, a fragment of the rim being seen in inverted plan.

Fig. 4 is a perspective view of one of the lock-receiving members detached.

Figs. 5, 6 and 7 are views of an embodiment of the lock-receiving element detached.

Figs. 8, 9 and 10 are similar views of a further embodiment.

Fig. 11 is a plan view of a fragment of the inner face of a modified form of rim.

Fig. 12 is a cross section taken on the plane indicated by line 12—12 of Fig. 11.

Referring to the drawing by numerals, 1 indicates the felly, 2 the fixed rim, and 3 the demountable rim of a wheel of the type fully disclosed in my above-identified co-pending application. For purposes of rendering the disclosure self-contained in this application, it will be seen that the wheel

portion is provided with locking apparatus, preferably several in number, spaced uniformly about the wheel and consisting essentially of a radially moving bolt 4 slidably mounted in a sleeve 5 anchored in the peripheral portion of the wheel, the sleeve being engaged by a nut 6 arranged to actuate the bolt 4 by having an underhanging annular flange 6' engage a shoulder 7 at the inner end portion of the bolt 4. A cotter-pin-retained nut 8 is arranged beneath the flange 6' in engagement with the reduced projection of the bolt, so that when the nut 6 is threaded radially inward the bolt 4 will be retracted and reverse movement of the nut 6 will project the bolt 4. A flattened portion 4' is provided on the bolt 4 to engage a correspondingly flattened portion within sleeve 5 to prevent rotation of the bolt and to keep its outer end properly aligned with the co-operating part of the rim 3. The bolt 4 is shown with its outer end formed with a V-shaped tapered upper end so that the rim 3 is provided with a correspondingly tapered recess elongated in the direction of the circumference of the wheel, but, of course, the upper end of the bolt 4 may be otherwise formed, as, for example, as seen in my above-mentioned co-pending application. In that event, the form of lock-receiving means on the rim would have to be correspondingly formed. As the said co-pending application covers the locking means itself, except for the specific form of taper at the outer end of the bolts, it is understood, of course, that this invention is more particularly directed to the lock-receiving means of the rim.

In the said co-pending application the lock-receiving means is provided by rolling or otherwise forming a continuous annular bolt-receiving member on the rim itself. While this has proved very effective and satisfactory, it requires additional stock and additional manipulation which increase the cost of production. Furthermore, it is not practical to roll or otherwise form on rims already in use the lock-receiving means such as shown in my co-pending application.

The rim 3, therefore, is perforated at preferably uniformly spaced points, the perforations being of a size and shape to snugly receive the rectangular upstanding boss 9 carried by plate 10. The plate 10 is preferably disk-shaped and formed integral with the boss 9, and a recess 11 is formed through the

material of the plate within the boss 9 from the under face of the plate, the said recess being of a contour to receive the upper end of the bolt 4. As the bolt 4 is of an inverted V-shape, the recess 11 is of a corresponding shape in cross section, but is preferably elongated in the direction of the circumference of the rim so as to allow of a slight variation of adjustment of the rim when it is being applied, the recess 11 being of a length in excess of the dimensions of the tapered end of the bolt. The plate 10 is welded or otherwise appropriately fixed to the base of the rim, and the boss 9 is proportioned to snugly fill the respective aperture in the rim. It will thus be seen that the lock-receiving means of the rim may be applied as well to rims now in use as to new rims. The apertures for receiving the bosses 9 are positioned midway of the width of the rim. The stop flange on the rim 2, however, is so spaced relative to the median line of the rim that the effect is the same as if the recess 11 were off of the said median line in the direction toward the outer face of the wheel, whereby when the bolt 4 is forced outwardly into the recess 11 it will act to wedge the rim axially against the stop flange and even after the rim has been seated firmly there will still be a sufficient lateral offset of the lock-receiving portion of the rim (that is, the material at the respective side of recess 11) to enable the bolt 4 to tend to further crowd the rim axially against the stop flange when the bolt is further pressed radially outward.

In Figs. 5, 6 and 7, I have illustrated a further embodiment of the lock-receiving means wherein the disk-shaped plate 10" is employed having the circular boss 9" and being formed with the recess 11", all of said parts corresponding in function and substantially in form with the respective parts 10, 9 and 11 above described.

In Figs. 8, 9 and 10, I have shown a modified embodiment of the invention in which a plate 10' is provided corresponding in form and function to the plate 10 except that the plate 10' is rectangular. The plate 10' is provided with the boss 9' having the recess 11', both corresponding in form and function to the respective parts 9 and 11.

In the application of the lock-receiving means, it is obviously essential that the groove 11 shall be accurately positioned in the line of the circumference of the rim and not set at an angle to such plane. Even a slight angular disposition of the parts would be injurious and interfere with the effective operation of the parts. It is thus obviously preferable to have the apertures in the base of the rim and the corresponding bosses either of rectangular form or other poly-sided form so as to insure the proper location of the bolt-receiving recess. The circular form of boss may also be used with the exer-

cise of care to see that the recess is properly located, and this form of boss will be found desirable, where the operator who is applying the part has facility for drilling a hole but has no facility for punching one.

In the above described embodiments of the invention, the lock-receiving groove member is made of a separate piece of material from the rim and inserted through an aperture in the rim. The same results may be obtained so far as the short segmental sections of grooves spaced apart about the rim are concerned by stamping such sections of grooves directly in the rim after the manner seen in Figs. 11 and 12. In these figures, the rim 3' is stamped to form the recess of groove 3", the material of the rim being pressed radially outward to form the recess. In the course of pressing the recess 3" the material of the base of the rim may be somewhat reduced in thickness, but the reduction is comparatively slight and no attempt at showing such reduction is made in the drawings. Care is exercised to see that the projection 3a which results from the forming of the recess of short section of groove 3" is rounded and has no broken edges or corners, and the ends of the groove section 3" are closed at 3b so that there is no danger of injury to the inner tube and no possibility of the tube being blown through the rim. The recess or groove sections 3" are preferably spaced uniformly about the rim and located relatively to the edges of the rim in such manner as to enable the rim to be applied with either edge 100 first. It is also noted that the groove sections 3" are segmental since they extend part the way in the direction of the circumference of the rim and are of a greater length than the corresponding dimension of the V-shaped lock which is designed to engage them. This relative proportion enables the locks to engage the groove sections even though the section may not be spaced exactly the same distance apart as the locks.

What is claimed is:—

1. In a demountable rim structure, the combination with an apertured demountable rim, of a part having lock-receiving means, the said part being adapted to extend through and fill the aperture in the rim, and the lock-receiving means being of greater length than width and being disposed with its length extending circumferentially of the rim.

2. In a demountable rim, the combination with a rim, of a plate secured thereto and having a boss extending through the rim, the boss being formed with lock-receiving means of greater length than width and with the length of the lock-receiving means extending circumferentially of the rim.

3. In a demountable rim, the combination with a rim, of a plate secured to the inner face of the rim and having a boss of rec-

tangular form extending outwardly through the rim, the said boss being formed with an elongated recess adapted to receive rim locking means, the recess being elongated circumferentially of the rim.

4. In a demountable rim, the combination with a rim, of a plate secured to the inner face of the rim and having a boss of rectangular form extending outwardly through the rim, the said boss being formed with an

elongated recess adapted to receive rim locking means, the recess being elongated circumferentially of the rim, the recess being of V-shape in cross section.

In testimony whereof I affix my signature 15 in presence of two witnesses.

LOUIS H. PERLMAN.
